UNITED STATES PATENT OFFICE.

JOSEPH E. VORBACH, OF NEW YORK, N. Y.

DESIGN FOR A NECKTIE RACK.

Application filed March 12, 1929. Serial No. 30,437. Term of patent 14 years.

To all whom it may concern:

Be it known that I, JOSEPH E. VORBACH, a citizen of the United States, residing at New York city, in the county of New York and State of New York, have invented a new, original, and ornamental Design for Necktie Racks, of which the following is a specification, reference being had to the accompanying drawing, forming part thereof.

The figure is a perspective view of a necktie rack, showing my new design.

I claim:

The ornamental design for a necktie rack as shown.

JOSEPH E. VORBACH.
